(57) **CLAIM**

The ornamental design for a hammer handle, as shown and described.

DESCRIPTION

FIG. 1 is an exploded front and right side isometric view of a hammer handle embodying my new design, wherein a hammer head is shown in broken lines;

FIG. 2 is an exploded rear and left side isometric view of the hammer handle;

FIG. 3 is front elevational view thereof;

FIG. 4 is a right-side elevational view thereof;

FIG. 5 is a left-side elevational view thereof;

FIG. 6 is a rear elevational view thereof;

FIG. 7 is a top plan exploded view thereof;

FIG. 8 is a bottom plan exploded view thereof; and,

FIG. 9 is a partial cross-section view thereof, taken along lines 9-9 as seen in FIG. 2.

The broken lines represent environmental structure and form no part of the claimed design.
